Fig. 1

Fig. 2

Fig. 3

FIG. 8

FIG. 6

FIG. 1

FIG. 1 is a side elevational view of a windbreaker for vehicles, showing my new design, it being understood that the broken lines are for illustrative purposes only;

FIG. 2 is a front elevational view thereof;

FIG. 3 is a top plan view thereof;

FIG. 4 is a side elevational view on an enlarged scale of a wind breaker for vehicles showing a second embodiment of my new design, wherein the sole difference resides in the configuration of the sides;

FIG. 5 is a side elevational view on an enlarged scale of a windbreaker for vehicles showing a third embodiment of my new design, wherein the sole difference resides in the configuration of the sides;

FIG. 6 is a sectional view taken on the line 6—6 of FIG. 4;

FIG. 7 is a sectional view taken on the line 7—7 of FIG. 5; and

FIG. 8 is a sectional view taken on the line 8—8 of FIG. 5.

The undisclosed side of the embodiments shown in FIGS. 1, 4 and 5 is substantially a mirror image of the

side shown in the respective views, except for the omission of the circular opening for the vehicle exhaust. The front and top of the embodiments shown in FIGS. 4 and 5 are the same as the front and top shown in FIGS. 2 and 3 respectively.

I claim:

The ornamental design for a windbreaker for vehicles, as shown and described.
